(57) **CLAIM**

The ornamental design for a hand-held barcode scanner, as shown and described.

DESCRIPTION

FIG. 1 is a perspective view of the hand-held barcode scanner;

FIG. 2 is a top plan view of the hand-held barcode scanner;

FIG. 3 is a left side elevational view of the hand-held barcode scanner. The right side elevational view is a mirror image of the left side;

FIG. 4 is a bottom plan view of the hand-held barcode scanner;

FIG. 5 is a front elevational view of the hand-held barcode scanner; and,

FIG. 6 is a rear elevational view of the hand-held barcode scanner.
